UNITED STATES PATENT OFFICE.

JAY B. KIRK, OF IOLA, KANSAS.

CLEANING DEVICE.

Application filed February 16, 1921. Serial No. 445,568.

To all whom it may concern:

Be it known that I, JAY B. KIRK, a citizen of the United States, and resident of Iola, in the county of Allen and State of Kansas, have invented a new and Improved Cleaning Device, of which the following is a full, clear, and exact description.

My invention relates to a cleaning device, and aims to provide improvements in connection with devices of this character.

With regard to apparatus permitting of the distillation of carbonaceous material, it is a well appreciated fact that difficulty has been experienced in connection with the carbon impinging against the side walls of the compartment within which it is deposited. The accumulation thus formed rapidly enlarges to such an extent as to seriously interfere with the operation of the device, aside from the fact that the apparatus provided for the removal of the carbon from the chamber is incapable of performing its function with respect to the side walls and roof of the chamber, which it does not engage.

Aside from this difficulty, the accumulation in some instances becomes freed, incident to the vibration of the machine, or on account of its own weight, and when this occurs, a large mass of carbon comes into contact with the apparatus provided for the removal of the same, and in some instances, results in a jamming of this apparatus incident to the fact that the conveyor is not constructed to handle particles of the size presented.

This difficulty has been experienced in connection with apparatus providing structure such as is embodied in my co-pending application, Serial #393515 in which it will be noted that a chamber is provided, which chamber has an endless conveyor co-operating with its base portion, said conveyor serving to remove the deposits from the chamber.

It is further to be understood that although I have illustrated my invention as applied to the structure illustrated in connection with my co-pending application, that the same may be utilized to advantage in various embodiments.

Thus reference is had to the attached sheet of drawings, as illustrating one practical embodiment of my invention, and in which;

Figure 1 is a fragmentary sectional side view taken through an apparatus to which my cleaning device is applied, and

Figure 2 is a sectional end view taken along the line 2—2 and in the direction of the arrows indicated in Figure 1.

In these views the reference numeral 5 indicates the trough in which the carbonaceous material is deposited through chutes 6, and in the usual manner, is removed therefrom through a discharge pipe 7, by any suitable type of conveyor such as a spiral 8, it being noted that a shaft drive 9 may serve to rotate the shaft upon which the spiral 8 is mounted.

It is now to be noted that the difficulty set forth in the preamble occurs, more particularly with regard to the side walls of the trough 5 upon which the accumulations are deposited, and which the conveyor is incapable of engaging, and with this in view, it will be noted that I preferably utilize a pair of shafts 10 extending longitudinally of the trough 5, said shafts being arranged upon opposite sides of the center of said trough.

To properly drive these latter shafts, I may conveniently utilize any suitable type of drive 11 connecting with the drive 9, and receiving motion therefrom, it being noted that gear wheels 12 affixed to each of the shafts 10, may serve to synchronize the motion of the same, and cause a rotation of these elements in opposite directions.

Each of the shafts carry fingers 13 arranged in staggered relation with respect to each other, and it will be seen that these fingers are mounted in such a manner that both sets of the same extend centrally or outwardly, at the same instant, it being further noted that the mounting of the shafts 10 is such as to permit of the fingers 13 clearing the spiral 8, although these fingers contact subsequently with the side walls of the trough 5 throughout a relatively large portion of their surface.

Thus it will be seen that by means of my improved construction, the side walls of the trough will be at all times subjected to a scraping action, effectually removing any particles which have impinged thereon, so that danger of the entire machine becoming choked, incident to these accumulations within the trough, or a jamming of the conveyor due to receiving large particles of accumulation is eliminated.

Obviously my invention might be placed in a number of different associations and

modified in structure without in the slightest departing from the scope of my claims, which are—

1. A cleaning device including a trough, 5 a conveyor adjacent the base of said trough, and centrally positioned within the same, shafts arranged within said trough and above said conveyor, said shafts being disposed to the sides of the center of said 10 trough, cleaning means carried by said shafts, and means for actuating said shafts and said conveyor.
2. A cleaning device for use with apparatus employed in the distillation of carbonaceous material and comprising a trough

into which the material to be carried off is received, a conveyor operating along the base of the trough for carrying off the material and cleaning means independent of the conveyor and arranged within the 20 trough, said cleaning means being disposed above the conveyor and operating along the entire length thereof and being positioned to operate against the walls of the trough to break up into small particles 25 deposits of carbonaceous material tending to build up on the wall of the trough and to throw such particles onto the conveyor.

JAY B. KIRK.
